TOY PARKING METER

Michael I. Satten, 245—20 Grand Central Parkway,
Bellerose, N.Y. 11426

Filed Jan. 23, 1975, Ser. No. 543,485

Term of patent 14 years

Int. Cl. D21—01

U.S. Cl. D34—15 R

FIG. 1 is a front elevational view of a toy parking meter showing my new design;

FIG. 2 is a right side elevational view thereof;

FIG. 3 is a rear elevational view thereof;

FIG. 4 is a top plan view thereof; and

FIG. 5 is a bottom plan view thereof.

I claim:

The ornamental design for a toy parking meter, as shown.
